UNITED STATES PATENT OFFICE.

JOHN F. O'CONNOR, OF CHICAGO, ILLINOIS, ASSIGNOR TO WILLIAM H. MINER, OF CHAZY, NEW YORK.

ROLLER SIDE BEARING.

1,251,090.

Specification of Letters Patent. Patented Dec. 25, 1917.

Application filed July 13, 1916. Serial No. 109,010.

To all whom it may concern:

Be it known that I, JOHN F. O'CONNOR, a citizen of the United States, residing at Chicago, in the county of Cook and State 5 of Illinois, have invented a certain new and useful Improvement in Roller Side Bearings, of which the following is a full, clear, concise, and exact description, reference being had to the accompanying drawings 10 forming a part of this specification.

This invention relates to improvements in roller side bearings.

One object of the invention is to provide a simple, relatively cheap roller side bearing 15 for railway cars and so arranged that the roller will be automatically returned to central or normal position after each actuation.

Another and more specific object of the 20 invention is to provide a spring controlled, roller side bearing wherein the roller is returned to normal after actuation, by a combined bending and torsional action of the spring.

25 In the drawing forming a part of this specification, Figure 1 is an end elevation of portions of a body and truck bolster showing my improvements in connection therewith. Fig. 2 is a horizontal sectional view, upon an enlarged scale, of the improved side bearing proper. Fig. 3 is a longitudinal, vertical section of the structure illustrated in Fig. 2 and taken on the line 3—3 thereof. Fig. 4 is a detailed sectional view 35 taken substantially on the line 4—4 of Fig. 2. And Fig. 5 is a perspective view of the spring attaching block employed.

In said drawing, 10 denotes the body bolster and 11 the truck bolster which are 40 pivotally connected at their centers in the usual manner. As shown, the body bolster is provided with a striking plate 12 and the truck bolster has applied thereto the improved side bearing designated generally 45 by the reference A.

The improved side bearing A preferably 50 comprises a base member or casting B which is riveted or otherwise suitably secured to the truck bolster, and an anti-friction roller C. The base member B is of substantially box-like form, open at the top and has outwardly extended bottom flanges 13 through which pass the securing means, and on its interior, the base member is provided with

a suitable inserted tread or wear plate 14 55 on which the roller C operates.

The base plate or retaining member B is provided with side walls 15 and 16, and end walls 17—17, the latter being outwardly convexed as indicated at 18—18 in Fig. 3. The 60 roller C is provided with a central opening 19 which is flared at one end as indicated at 20. At the opposite end, the opening 19 is made of rectangular form as indicated at 21 and has fitted therewithin a spring retaining block 22. The latter is recessed on its inner face as indicated at 23, to receive the end of the spring 24. Within said recess, the block 22 is provided with a pair of spaced lugs 25—25, over which fit the 70 coils of the spring and between which extends the bent end 26 of the spring so that relative turning movement between the spring and the roller C is prevented. The side wall 15 of the base casting or roller 75 retaining member is provided with a hollow offset boss 27 which is flared as indicated at 28 to correspond with the flare 20. On the inner side of the end wall of the hollow boss 27, are provided two inwardly extending lugs 29—29, over which fit the end 80 coils of the spring 24 and between which extends the bent end 30 of the spring, thus preventing rotation of the spring with respect to the said boss 27. 85

As the roller C is actuated, it is apparent that it will be moved to one side or the other and in so doing, the spring 24 will be flexed or bent as an entirety, this movement being accommodated by the flared 90 openings 20 and 28. In addition to said bending of the spring 24, it is apparent that the spring will be twisted. When the roller is moved to one side, this additional twist or torsion will be in the same direction as the inherent twist of the spring and when moved in the opposite direction, the twist or torsion created will be opposed to the inherent twist of the spring. In either direction, the torsional effect thus created 100 will assist in more certainly returning the roller to normal or central position. It will be understood that the roller C is limited in its movements by the end walls 17—17.

From the preceding description, it will 105 be seen that I have provided a roller side bearing which may be relatively cheaply manufactured; wherein is employed a roller

of comparatively large diameter presenting a wide bearing surface; and wherein the roller is always returned automatically to normal position after each actuation.

5 I claim:

1. In a roller side bearing, the combination with a retaining member, and a roller bodily movable therein, of means for returning said roller to normal position after actuation thereof, said means comprising, a spring extending between said member and the roller, said spring being non-rotatably secured to said member and the roller, whereby the end of said spring which is attached 15 to the roller, is rotated in unison with the rotation of the roller.
2. In a roller side bearing, the combination with a retaining member, and a roller bodily movable therein, of means for returning said roller to normal position after actuation thereof, said means comprising, a spring non-rotatably secured to said member at one end, the other end of said spring being extended into the roller axially thereof, the end of the spring within the roller being also non-rotatably secured to the roller.
3. In a roller side bearing, the combination with a retaining member, and a roller bodily movable therein, of means for returning said roller to normal position after actuation thereof, said means comprising, a spring secured at one end to said member and at its other end to the roller, said member and said roller being each provided with normally aligned openings into which the ends of the spring extend.
4. In a roller side bearing, the combina-

tion with a hollow base casting, one of the walls thereof being provided with a hollow boss, of a roller mounted within said base casting, the roller being provided with a centrally located recess normally aligned with said hollow boss, and a spring having its ends extended into said hollow boss and the recess in said roller, the ends of said spring being fixed with respect to the hollow boss and said roller, respectively.

5. In a roller side bearing, the combination with a hollow base casting having a flared opening in one of its walls, of a roller mounted within said base casting, the roller having a centrally located recess which is flared toward said flared opening in the base casting, and a spring having its ends extended into said opening and attached at its ends respectively to the base casting and said roller.

6. In a roller side bearing, the combination with a base casting, of a roller, a spring extending between said base casting and roller, and means for non-rotatably securing one end of said spring to the roller, said means comprising, a block of non-circular form mounted in a correspondingly shaped recess in the roller, said block being provided with a pair of spaced lugs over which the end of the spring fits and between which the extreme bent end of the spring is located.

In witness that I claim the foregoing I have hereunto subscribed my name this 11th day of July, 1916.

JOHN F. O'CONNOR.
